Primary Examiner — Richard Edgar*Assistant Examiner* — Bryan N. Melvin(74) *Attorney, Agent, or Firm* — Daniel M. Cohn; Howard M. Cohn(57) **CLAIM**

The ornamental design for a connector for strip light as shown and described.

DESCRIPTION

FIG. 1 is a perspective view of a connector for strip light showing our new design;

FIG. 2 is another perspective view thereof;

FIG. 3 is another perspective view thereof;

FIG. 4 is a perspective view in a state of use;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines in the drawings depict portions of the connector for strip light that form no part of the claimed design.

1 Claim, 10 Drawing Sheets(56)
